UNITED STATES PATENT OFFICE.

JOSHUA B. BERSTLER, OF LANCASTER, PENNSYLVANIA, ASSIGNOR, BY MESNE ASSIGNMENTS, TO SAFETY MANUFACTURING COMPANY, OF LANCASTER, PENNSYLVANIA, A CORPORATION OF DELAWARE.

EMERGENCY DOOR-LOCK.

1,058,346.

Specification of Letters Patent.

Patented Apr. 8, 1913.

Application filed February 6, 1912, Serial No. 675,700. Renewed September 7, 1912. Serial No. 719,163.

To all whom it may concern:

Be it known that I, JOSHUA B. BERSTLER, citizen of the United States, residing at Lancaster, in the county of Lancaster and 5 State of Pennsylvania, have invented certain new and useful Improvements in Emergency Door-Locks, of which the following is a specification.

This invention relates to improvements 10 in emergency door locks and the object is to provide a device of this class in which the lock may be operated by pressure from the inside and by turning the lock knob from the outside.

15 The principal object in the present instance is to produce a device of this character that will be as simple as possible, and yet prove effective in action.

The invention consists of a front plate, 20 with a knob so placed therein that it will be free to move toward and away from the door, by pressure being applied directly to it, and a pair of levers so placed within the plate that the inner edge of the knob 25 will operate them to withdraw the upper and lower door locking bolts simultaneously.

A further object is to provide a simple means for operating both of the locking bolts from the outside by merely turning 30 the outside knob.

The invention is more fully described in the following specification and clearly illustrated in the accompanying drawings in which:—

35 Figure 1 is an elevation of a pair of doors with my lock applied thereto, showing the inside of the doors. Fig. 2 is a central, vertical sectional view of the device as applied to the door. Fig. 3 is a detail view 40 showing the outside knob operating means for operating the bolts. Fig. 4 is a detail of the bolt. Fig. 5 is a detail of the bolt engaging end of the operating rod. Fig. 6 is a detail of the bolt guide and Fig. 7 45 is a detail of the lever supporting plate.

The numeral 1 designates the door, 2 the inner plate and 3 the inner knob. The plate 2 is formed with an inwardly curved hollow portion 4, the inner extremity of 50 which is formed with a cylindrical neck 5 and this neck is formed with a horizontal guide slot 6.

The knob 3 fits loosely in this neck, and

its shank 7 is provided with a pin 8 adapted to ride in the slot 6.

55

In the curved hollow portion of the plate I secure a lever supporting plate 9, formed with a pair of side ears 10 and in these ears I place a pair of oppositely movable levers 11, the inner or free ends of which 60 are in line with the inner end of the knob shank, and to the opposite ends of these levers I secure the inner ends of a pair of bolt operating rods 12. Each of these rods is formed at its other end with a hook 13 65 adapted to engage an opening 14 in one of the locking bolts 15, one of which bolts is adapted to engage the upper and the other the lower door frame. These bolts move in guide ways 16 cut into the door and a guide 70 plate 17 is placed over these ways which plates serve to keep the bolts in proper position. These plates are formed with elongated slots in the front face, 18, and a pin 19 which screws into the bolt moves in this 75 slot and serves to keep the bolt in proper position, and together with two lugs 20 formed on the plate serves as a means for keeping the bolt in alignment. The bolts are backed by coiled springs 21, which serve to keep 80 them normally shot and against the tension of which the bolt operating rods 12 and the levers 11 operate. It is evident therefore that when pressure is put on the knob 3, the levers are opened and the operating rods 85 12 are drawn inwardly, toward the knob center, thus withdrawing the bolts 15 and permitting the door to be opened.

The means for opening the door from the outside consist of a knob 22, on the inner 90 end of the shank 23 of which I place a disk 24 and on this disk I place two headed pins 25 near the outer edge, diametrically opposite each other. On the inner ends of the operating rods 12, I attach plates 26, each 95 of which is formed with an elongated slot 27 and in these slots I arrange a pair of headed rods 28, adapted to move therein, and whose inner ends are pivotally secured to the headed pins on the disk. It will be 100 seen therefore, that when the knob 22 is turned, the rods 28 will draw the operating rods 12 toward the lock center and retract the locking bolts.

The slots 27 in the plates 25 will permit 105 the plates to move when the inner knob is

operated without turning or affecting the outer knob, just as the outer knob when turned will not affect the inner knob, for the reason that the inner ends of the levers 11
5 are normally free from contact with the inner edge of the inner knob shank.

Having thus fully described my invention what I claim and desire to secure Letters Patent is:—

- 10 1. In an emergency door lock the combination of an inner plate provided with a central neck, a guide slot in said neck, a hollow inner knob provided with a pin adapted to move in said neck, a lever supporting plate secured within the plate, a pair of levers pivotally arranged on said plate and adapted to be operated by the said knob, a pair of bolt operating rods connected to the inner ends of the levers, hooks on the outer ends of said rods, bolts formed with openings adapted to receive said hooks, springs for keeping the bolts normally shot, guide plates for the bolts, pins on the bolts projecting through slots in the guide plates,
15 20 25 30 35
- plates provided with slots secured to the inner ends of the operating rods, headed rods adapted to move in said slots, an outer knob, a disk on the inner end of said knob and pins on the disk in pivotal engagement with the inner ends of said headed rods.
2. In an emergency door lock the combi-

nation of a plate formed with a central opening, a knob movably secured in said opening, a pair of levers secured within the plate and in line with the shank of said 35 knob, operating rods connected to said levers, locking bolts on the outer ends of said operating rods, springs to keep the bolts normally shot guide plates for the bolts, an outer knob, a disk secured to the knob, and 40 rods connecting the disk with the operating rods.

3. In an emergency door lock the combination of an inner knob, a plate formed with an opening to receive the shank of the knob, 45 a pair of bolt operating levers pivoted within the plate, the free ends of which are adapted to be actuated by the knob shank, bolt operating rods connected to the inner ends of the levers, spring backed bolts on 50 the outer ends of the operating rods, guide plates for the bolts, an outer knob, a disk on the shank of the outer knob and rods connecting the disk with the bolt operating rods.

In testimony whereof I affix my signature in presence of two witnesses.

JOSHUA B. BERSTLER.
